CONVERTIBLE CHESS AND CHECKER GAME PIECE

Paul R. Gruber, Waterbury, Conn.

Application October 17, 1938, Serial No. 235,338

5 Claims. (Cl. 273—137)

This invention relates to improvements in games, and more particularly to a combination chess and checker game piece which may be used on a common "checker" board and which may be readily changed from one form into the other.

The objects of this invention are to provide an improved chess and checker game piece of the above nature which will be relatively inexpensive to manufacture, simple in construction, compact, ornamental in appearance, and very efficient and durable in use.

With these and other objects in view, which will appear as the description proceeds, there have been illustrated in the accompanying drawings several forms in which the invention may be conveniently embodied in practice.

In the drawing:

Fig. 1 is a top plan view of a common game board as it appears with a set of chess men arranged thereon in playing position.

Fig. 2 is a side view of a combination game piece having a detachable upper chess portion representing a "knight."

Fig. 3 is a top plan view of the game piece shown in Fig. 2.

Fig. 4 is an enlarged top plan view of one of the base members or checker playing discs with the chess playing upper portion removed therefrom.

Fig. 5 is a sectional view of the same, taken on the line 5—5 of Fig. 4.

Fig. 6 is a broken sectional view of the same, taken on the line 6—6 of Fig. 4.

Fig. 7 is an enlarged bottom view of the upper chess portion of the game piece.

Fig. 8 is a broken view of the lower part of the chess portion shown in Fig. 7.

Fig. 9 is a plan view of a modified form of checker member or base piece to which an upper chess portion may be detachably secured.

Fig. 10 is a broken side view of the same with a chess portion connected thereto.

Fig. 11 is a perspective view of a circular chess portion embodying a modified form of the invention.

Fig. 12 is a view of one of the playing squares of a game board having a recess for detachably receiving a chess playing portion of the two-part game piece.

Referring now to the drawing wherein like reference numerals denote corresponding parts throughout the several views, the numeral 10 denotes a common type of game board having eight rows of alternating black and white squares 11 thereon, and adapted for the playing of both

chess and checkers. Two opposing sets of chess playing pieces or "men", sixteen in each set, are shown in playing position on the board 10 in Fig. 1, said men preferably being made in contrasting colors not indicated on the drawing. 5 The men of each set comprise the usual two castles 12, two knights 13, two bishops 14, a king 15, a queen 16, and eight pawns 17. These playing pieces each comprise upper and lower portions and are adapted to be converted into 10 checker pieces by the simple expedient of removing the upper chess portion from its base or checker disc 18.

In Fig. 2, a composite game piece is shown including the common form of checker base 18 15 and an upper chess portion 19 representing a "knight." The chess portion 19 in this instance is formed from flat sheet material, such as "Bakelite", and is preferably manufactured by stamping or molding it in a die from a sheet with the 20 desired configuration embossed on both of its opposite side surfaces. The "checker" disc 18 may likewise be stamped or molded from similar sheet material.

In order to detachably connect the upper chess 25 portion 19 to the lower checker disc 18 to provide a composite chess piece, the portion 19 is provided with a depending tongue 20, which is adapted to be manually inserted into a "keyhole" shaped recess 21 provided in the disc 18. The 30 tongue 20 is dovetail in form transversely to the plane of the portion 19, and has oppositely inclined sides 22 and 23 curved to tightly fit a pair of corresponding dovetail shaped undercuts or cam surfaces 24 and 25 in the base disc 18. 35

In manufacturing the chess portions 19, the beveled sides 22 and 23 are first formed straight across the tongue 20 as indicated by dotted lines in Figs. 7 and 8, and are then curved in any suitable manner to cause said sides to tightly 40 fit the dovetail undercuts 24 and 25.

The keyhole opening 21 in each disc 18 is preferably made substantially rectangular and the undercut 24 diverges downwardly, as shown in Figs. 5 and 6. The long dimension of each 45 rectangular opening 21 extends at right-angles to the axis of the dovetail undercuts 24 and 25, and said opening 21 is of proper dimensions to permit the free insertion of the tongue 20 thereto. After the tongue 20 has been inserted into 50 the opening 21, the chess portion will be given a quarter turn, as indicated by the arrow in Fig. 3, whereupon the dovetail sides 22 and 23 will be disposed in tight engagement with the dove-tail undercut cams 24 and 25 respectively. 55

A pair of parallel lines 26 and 27 are preferably marked on the upper surface of each base disc 18 (as shown in Figs. 3 and 4) to indicate when the sides of the chess portion 19 have reached the locked position in the base 18.

The base portion or disc 18 is also provided with a circular recess 28 in its undersurface, and a circular boss 29 upon its upper surface. The boss 29 of one checker disc is shaped to telescope into the recess 28 of another disc located below it, as indicated in dotted lines in Fig. 5, so as to prevent the upper checker disc 18 from slipping off when the lower checker is "crowned."

Modifications

15 In the modified form of game playing piece shown in Figs. 9 and 10, the numeral 30 indicates a base member or checker disc, and the numeral 31 an upper chess portion. The chess portion 31 is provided with a depending dovetail tongue 32 which is adapted to be slid from one side into a horizontal slot provided in the upper surface of the checker disc 30. The slot in the disc 30 is in two parts—a flat-sided outer portion 33 leading in from the edge of the disc, and a narrower dovetail inner portion 34 located at the center of the disc. The tongue 32 is first set in from above until it is seated in the portion 33, and then slid horizontally along into the dovetail portion 34 as far as it will go, whereby 30 the chess portion 31 will be centralized in respect to the checker disc 30, as shown in dotted lines in Fig. 9.

Fig. 11 illustrates a circular form of a chess portion 35, herein shown in the form of a pawn 17, being molded in cylindrical form instead of flat, as in the previously described forms of the invention. A dovetail tongue 36, similar in all respects to the tongue 20 supra, extends downwardly from the undersurface of the chess man 35 and is adapted to be interlocked with any one of the base discs 18.

In case it may be desired to play a game of chess using the upper chess portions only, a modified form of game board may be provided 45 in which keyhole recesses 37 are provided in the center of each of the squares 38, as indicated in Fig. 12. Each recess 37 is in all respects similar to the recess 21 in the discs 18. Also, parallel lines 39 and 40 may be embossed upon the squares 37 to indicate when the chess men are in locked position.

Operation

In operation, when it is desired to play a game 55 of chess, each of the various chess portions 19 will be interlocked with a base disc 18 by inserting its dovetail tongue 20 into the keyhole opening 21 in the disc 18 and rotating the chess portion 19 a quarter turn. The composite game 60 piece thus produced is then ready for use in playing the chess game. After the game of chess is finished and a game of checkers is desired, it will merely be necessary to remove the chess portions 19 from the base portions or checker 65 discs 18, which discs may then be employed to play the game of checkers in the usual manner.

One advantage of the present invention is that 70 different games may be selectively played with a single game board—in this instance, chess and checkers.

A further advantage is that the game board

and game pieces may be packed in a relatively thin container for convenience in storage or transportation.

While there have been disclosed in this specification several forms in which the invention may be embodied, it is to be understood that these forms are shown for the purpose of illustration only, and that the invention is not to be limited to the specific disclosures, but may be modified and embodied in various other forms without departing from its spirit. In short, the invention includes all the modifications and embodiments coming within the scope of the following claims.

Having thus fully described the invention, what is claimed as new, and for which it is desired to secure Letters Patent, is:

1. In a convertible two part chess and checker game piece, a checker-playing base disc having an undercut recess, an upper chess-playing portion having a dovetail tongue for insertion into said recess, and means to cause said chess-playing portion to be detachably interlocked with said base by the rotation of said portion a quarter turn with respect to said base. 20

2. In a chess game, a checker board provided with a plurality of rows of playing squares, each square having a vertical recess in the center thereof, and a plurality of chess pieces, each chess piece having a vertical tongue shaped to enter any of the recesses in said squares, and cooperating means between said tongue and said recesses to detachably interlock said chess pieces thereto in vertical position when the latter is turned through an angle about a vertical axis. 30

3. In a convertible two-part chess and checker game piece, a checker-playing base disc having an undercut recess, an upper chess-playing portion having a dovetail tongue for insertion into said recess, and means to cause said chess-playing portion to be detachably interlocked with said base by the rotation of said portion a quarter turn with respect to said base, and means on said base portion to indicate when said upright portion is in locked position. 40

4. In a convertible two-part chess and checker game piece, a checker-playing base disc having an undercut recess, an upper chess-playing portion having a dovetail tongue for insertion into said recess, and means to cause said chess-playing portion to be detachably interlocked with said base by the rotation of said portion a quarter turn with respect to said base, each disc being provided with a circular recess in its bottom surface and a circular boss on its upper surface to permit said checker disc to interfit with a similar disc placed upon it. 50

5. In a convertible two-part chess and checker game piece for playing upon a common checker board, a checker-playing base disc having in its upper portion an undercut recess, an elongated keyhole slot in the upper portion of said disc opening into said recess, an upper chess-playing portion having a depending tongue for detachable interlocking engagement with said slot, said tongue being elongated in one direction to permit it to be inserted into said slot and then twisted through an angle to detachably lock it in said base, the removal of said upper portion permitting the use of said disc for playing 65 checkers. 60
